UNITED STATES PATENT OFFICE.

BENJAMIN F. MODISSETT, OF HELENA, ARKANSAS.

BICYCLE.

SPECIFICATION forming part of Letters Patent No. 727,405, dated May 5, 1903.

Application filed October 9, 1902. Serial No. 126,443. (No model.)

To all whom it may concern:

Be it known that I, BENJAMIN F. MODISSETT, a citizen of the United States, and a resident of Helena, in the county of Phillips and State 5 of Arkansas, have invented new and useful Improvements in Bicycles, of which the following is a full, clear, and exact description.

My invention relates to improvements in bicycles; and one object that I have in view 10 is the provision of a simple and strong construction in which the parts are organized in a new way, so as to bring the carrying-wheels into parallel relation and to suspend the weight of the load close down to the ground, 15 thus enabling the rider to mount and dismount with comparative ease, overcoming the tendency of the wheels to slip below the rider and enabling the rider to use his efforts to the best advantage in securing fast speed of 20 the machine.

A further object is to provide an improved steering device by which the rider is able to control the wheels separately by levers placed within convenient reach of the hands, and 25 these levers may be shifted so as to steer the machine on any desired course or to simultaneously move the wheels to inclined positions for arresting the machine without a brake.

A further object is to equip the machine 30 with an improved propelling mechanism adapted to use the power of the hands and feet in such a way as to secure high speed.

A further object is to so mount the frame on the axles as to cushion the vibration of 35 the seat and to reduce the shock when one of the wheels drops into a rut or depression in the road.

Further objects and advantages of the invention will appear in the course of the sub- 40 joined description, and the novelty will be defined by the claims.

Reference is to be had to the accompanying drawings, forming a part of this specification, in which similar characters of reference indicate 45 corresponding parts in all the figures.

Figure 1 is a side elevation of a portion of my bicycle, illustrating the carrying-frame and one of the axles, partly in section, and omitting the seat, the driving and steering 50 mechanisms, and the canopy. Fig. 2 is a detail view through a part of a wheel-felly. Fig. 3 is a vertical cross-section through the

machine, omitting both of the carrying-wheels. Fig. 4 is a front elevation of the complete bicycle. Figs. 5, 6, 7, 8, and 9 are detail views of the several parts comprising the hub. Fig. 10 is a detail view, in side elevation, partly in section, of one of the slideable bearings. Figs. 11, 12, 13, 14, 15, 16, 17, 18, and 19 are detail views of various parts, which will be hereinafter described. Figs. 20 and 21 are views in end and front elevation of the seat. Figs. 22, 23, and 24 are detail views of parts to be hereinafter described. Fig. 25 is an elevation of one member or section of the axle, showing by dotted lines the pivotal and sliding bearings associated with the axle; and Figs. 26 and 27 are enlarged detail views of parts of the carrying-frame.

My improved bicycle differs from those of ordinary make in many essential respects, chief among which is the arrangement of the wheels side by side or parallel to each other and the employment of the carrying-frame, which is suspended below the axle of the machine in order to bring the weight below the center of the structure. For the purpose of placing the rider's seat in the middle of the machine and for steering and guiding the apparatus the main axle is divided transversely into members or sections (indicated at A A', see Fig. 4.) On the outer ends of the axle members are secured the main wheels C, which are of large diameter, as shown by Figs. 1 and 4, and from the axle members is suspended the carrying-frame, which is equipped with the rider's seat and with the means for propelling the axle members and the wheels. The frame embodies in its construction a horizontal bar G, another horizontal bar D, the upright members x x', and suitable stays or braces. The horizontal bars G D are each continuous and extend nearly from one wheel to the other, as shown by Fig. 4, and the bar G is arranged a considerable distance below the horizontal plane of the axle and in the same vertical plane thereof, whereas the other continuous bar D is arranged well to the rear of the axle and nearly in the same horizontal plane as said axle. The horizontal bars D and G are connected at their end portions by diagonal braces H. (Shown in Fig. 1.) The frame members x x' extend vertically from the lower bar G, to which said frame mem-

bers are rigidly fastened, and these frame members are connected operatively with the axle-sections A A' by the pivotal bearings *t*. (Shown in Figs. 1 and 4 and by detail in Figs. 5 11 and 12.) These pivotal bearings are provided with openings *u* to loosely receive the outer end portions of the axle members, and said pivotal bearings are prevented from sliding on the axle members by the check-nuts *B*, which are screwed on the axle members so as to lie on opposite sides of the pivotal bearings. Each bearing *t* is provided with a depending stem *U*, which is arranged to fit loosely in a channeled or hollow upper portion 10 of the upstanding frame members *x x'*, and each frame member is provided with a head *x²*. (Shown more clearly by Figs. 11 and 12.) Said head *x²* of each frame member is provided with an opening, through which loosely 15 passes the stem *U*, and against the under side of this head bears a washer *w'*. A coiled cushioned spring *w* is loosely fitted around the depending stem of each bearing *t* in a manner to be housed within the hollow part 20 of the upstanding frame member, and one end of this spring acts against the washer *w'*, while the other end of said spring is seated against an adjustable nut *w²*, which is screwed on the lower threaded end of the 25 stem *U*, thus making provision for placing the spring under tension and for increasing or decreasing the energy of the spring, as may be required. It will thus be seen that the carrying-frame is loosely suspended 30 at its upper end corners from the outer portions of the axle members by means of the bearings which have pivotal connection with certain parts of the frame, and the vibration of the frame is absorbed or taken up to a 35 large extent by the employment of the cushion-springs *w*, which are operatively connected with the stems of the pivotal bearings and oppose the downward movement of the carrying-frame. The frame is connected at points 40 intermediate of its length to the inner portions of the axle members by means of 45 slideable bearings, the same being shown in Figs. 3 and 4 and in detail by Fig. 10. The inner end portion of each axle member is reduced, 50 as shown by Fig. 25, to form a tenon *a*, on which is screwed a nut *C'*, and this tenon of each axle member is fitted loosely in an opening 55 of the slideable bearing *k*, (see Fig. 9,) after which the nut *C'* is screwed on the tenon in order to coöperate with a shoulder on the axle 60 member for the purpose of holding the bearing *k* and the axle member in their proper positions. The slideable bearings *k* are fitted to the inner portions of the axle members so 65 as to lie on opposite sides of the rider's seat, as shown by Fig. 4, and these slideable bearings are provided with the sleeves *k'* and with the threaded studs *q*. (See Fig. 10.) The sleeves of the slideable bearings *k* are fitted 70 loosely on the horizontal arms *l*, which are rigidly fastened to the rear continuous frame-bar *D*, said horizontal arms extending for- 75 wardly from the frame-bar, so as to lie on opposite sides of the seat. The horizontal arms are supported at their front ends by means of braces *r*, which are fixed at their upper ends to the arms *l* and are suitably connected with a part of the carrying-frame. The sleeves *k'* of the bearings are free to slide for limited distances on the horizontal arms *l*, which form parts of the frame, and to the studs *q* of the slideable bearings are attached the front ends of the links *p*. The rear ends of the links are engaged by the hooks *m'* of the retracting-springs *m*, which are attached 80 to the frame-bar *D* by the eyebolts *n*, having the thumb-nuts *o*. (See Fig. 10.) The links, the springs, and eyebolts are disposed below the horizontal frame-arms *l*, so as to be out of the way and to occupy compact relation to 85 certain parts of the frame. The springs *m* normally draw the slideable bearings *k* rearwardly on the frame-arms *l*, so as to make these slideable bearings *k* align with each other and with the pivotal bearings *t*, and thus the 90 pivotal and slideable bearings are maintained in alined positions for the purpose of holding the axle members A A' in alinement with each other, whereby the wheels C are kept in parallel positions and the machine is made 95 to pursue a straight course.

I have provided means for individually shifting the slideable bearings and the axle members so as to steer the machine around a corner or in any desired course, and these 100 steering devices will now be described.

The lower frame-bar *G* is equipped at points intermediate of its length with the upstanding posts *q'*, which are rigidly fastened to said bar, and these posts, together with the 105 upstanding members *x x'* of the frame, are braced by the diagonal stay-rods *F*, two of which are provided on opposite sides of the seat. One stay-rod is fastened to the bar *G* and one post *p'*, the other stay-rod is fastened 110 to the bar *G* and the frame member *x* or *x'*, and the two stay-rods comprising the pair cross each other and are united at their point of intersection. (See Figs. 4 and 26.) The posts *q'* are provided with the upstanding 115 bars *p'*, each having an angular lug *p²*, (see Figs. 20 and 21,) and on the lugs *p²* are independently pivoted the guiding-levers *y y'*. (See Fig. 4.) Each guiding-lever is provided at its front end with a handpiece or 120 grip, while its rear end is pivoted to the lug of the post, and this lever is connected, by means of a link *y²*, with one of the slideable bearings, said link *y²* having a short link *z*, attached to the stud *q* or the link *p*, as shown 125 by Fig. 10. The steering-lever *y* is connected with its link *y²* by a brace *y³*, the opposite end of said brace being attached to the rear end of the lever *y* and the upper part of the link *y²*. (See Fig. 13.) It will be observed 130 that the levers *y y'* may be individually manipulated so as to draw one or both of the slideable bearings *k* in a forward direction and against the energy of the springs *m*, and

this movement of the bearings k adjusts one or the other of the axle members A or A' to the required position for changing the course of the machine.

5 The rider's seat n occupies a horizontal position over the frame-bar G and in front of the frame-bar D. This seat is disposed centrally within the machine, and at the end portions of the seat are provided the guides n', which are fitted slidably on the upright posts q', to which the steering-levers are fulcrumed. The seat n is provided near its end portions with depending guide-stems n², which are fixed to the under side of the seat and have their lower ends arranged to play freely in guide-plates n³, that are fixed to the top edge of the bar G, and around these guide-stems are fitted the coiled cushion-springs t', the latter serving to normally hold the seat 15 in an elevated position and to allow said seat to have a limited vertical movement on the frame. The springs also absorb the jar or vibration of the seat. The rider occupies a central position within the frame and is free to lean rearwardly against the back m², 20 which is attached to the seat by the bars s' and is braced by the rods r'. The seat n and the back m² may be cushioned or finished in any suitable way, and this is an obvious expedient. The seat is arranged between the 25 inner terminal portions of the axle members and in a horizontal position below said axle members, and said seat also lies between the guiding-levers y y', so that the levers are 30 within convenient reach of the right and left hands of the rider.

J designates a canopy arranged over the seat for the purpose of protecting the rider against the sun and the weather, and this 40 canopy is secured or mounted on the uprights O, which are fastened in a suitable way to the upper portions of the standards q², carried by the frame-bar G.

The propelling mechanism which I employ 45 is adapted for operation by the hands and feet of the rider, and the operating parts of this mechanism are mounted on a horizontal pivotal rod h', the latter being arranged in front of the seat and below the frame-bar G. (See 50 Fig. 3.) This pivotal rod is held in place by the bars k', arranged in the inclined positions shown by Fig. 3 and extending upwardly and rearwardly to the bar D, to which the frame-bars k² are fastened. These frame-bars are 55 stayed steadily in place by the braces i' and j', the braces i' extending rearwardly from the lower ends of the braces k², and are fastened to the frame-bar G, as shown by Fig. 3, while the other braces j' extend laterally from 60 the frame-bars k² and the braces i', so as to be fastened to the front sides of the frame-bar G, as shown by Fig. 4.

The pedals X are in the form of bails or loops, (shown more clearly by Fig. 18,) and 65 these pedals are fitted loosely on the end portions of the pivotal rod h', each pedal being held against lateral displacement by any suit-

able means. The pedals are provided with the stay-bolts l', and the rear stay-bolt on the pedal is associated with a clip f'. Each pedal is also provided at its front end with a stud g', to which may be connected a curtain adapted to inclose the rider and protect him from the rain. The pedals X have their front portions pivoted to the driving-rod Z, and these driving-rod extend upwardly and rearwardly to the driving-levers Z', one of which is shown in detail by Figs. 15 and 16. Each driving-lever Z' is forked or bifurcated and fitted loosely on the inner portion of one axle member, so as to embrace a ratchet z', fixed to one axle member. The driving-lever is thus loosely mounted on the axle member to have a rocking motion on an axis concentric with that of the ratchet z', and this driving-lever is adapted to turn the ratchet and the axle when the rod Z is pulled downward by the pressure on the treadle. The driving-lever is provided with pawls b', arranged to engage with the teeth of the ratchet, and these ratchets z' on the two axle members are driven individually by the levers, the rods, and the pedals. The rear end of each pedal has attached thereto a hand-actuated pull-rod W, having a handle W'. There are two of these 90 pull-rods and handles provided within convenient reach of the rider occupying the seat, and these rods are individually attached to the pedals, so that the rider is able to use the hands and the feet in driving the axles and wheels. The pedals are forced downward by the pressure of the rider's feet, so as to actuate the levers and the ratchets for the propulsion of the axles, and these pedals are 95 pulled down by the rider's hands and the rods 100 W, the pawls and ratchets being actuated by the pedals and the pull-rods to assist in the 105 propulsion of the machine.

In Fig. 15 of the drawings the driving-lever Z is provided with two pawls arranged 110 one above the other; but the lower pawl is adapted to serve as the means for rotating the ratchet when the pedal is forced down and the pull-bar is pulled up, the other pawl serving as a check to prevent backward turning of the ratchet. On the upstroke of the 115 pedal and the lever Z the pawls slip idly over the ratchet; but as the two pedals and pull-bars work alternately the machine is adapted to be propelled continuously.

Any suitable construction of wheels may be employed; but I prefer to use a double series of spokes in connection with the particular form of hub shown in Figs. 5 to 9, inclusive. The hub consists of the outside 125 plates d d', each having an inwardly-extended boss e, and between these plates is interposed a short sleeve J', having a radial plate J². The hub-sleeve J' is arranged between the plates d d', so that its plate J² will lie between 130 the two series of spokes a², and these spokes, with the several hub-plates, are fastened together by the rivets a³. The bosses e of the hub-plates are fitted on the outer end portion

of an axle member, and the wheel-hub is fastened to said axle member by the pins e' , which pass through the bosses e and said axle member. The spokes a^2 are fitted in

5 sockets of the wheel-felly b^2 and are secured in place by transverse rivets b^3 . The wheel felly or rim may be provided with a tire c^2 of any suitable character.

Having thus described my invention, I 10 claim as new and desire to secure by Letters Patent—

1. A bicycle comprising a divided axle, a suspended frame, means for pivotally and yieldably connecting said frame with the members of said axle, spring-controlled bearings supporting the inner ends of the axle members and normally holding the latter in alined relation, and steering-handles connected with said bearings.

2. A bicycle comprising a divided axle, a suspended frame, means for pivotally connecting said frame with individual members of said axle, spring-controlled bearings supporting the individual axle members, and separate steering-levers mounted on the frame and connected with said bearings.

3. A bicycle comprising a divided axle, a seat-frame suspended from the members of said axle, parallel wheels mounted individually on the axle members, a propelling mechanism, tension devices for normally holding the axle members in alined relation, and separate steering devices individually operable at will and connecting said members of said axle, and arranged to independently or simultaneously move them against the energy of their tension devices.

4. A bicycle comprising a divided axle, a seat-frame having a pivotal suspension connection with the members of said axle, wheels mounted on the members of the axle, independent sets of propelling devices connected individually with the axle members, separate tension devices connected with the axle members to normally hold them in alined relation, and independent steering devices operable at will and connected individually with the axle members to move the latter slidably against the energy of the tension devices.

5. A bicycle comprising a suspended seat-frame, a divided axle having each of its members connected pivotally with the seat-frame, bearings fitted slidably on said frame and supporting the inner portions of the axle members, springs controlling the slidable bearings and normally holding the axle members in alined relation, wheels mounted on the individual axle members, a propelling mechanism, and steering devices connected to the 60 slidable bearings for shifting said axle members.

6. A bicycle comprising a suspended seat-frame, a divided axle, bearings pivotally connecting the outer ends of the axle members 65 with the seat-frame, horizontally-slidable bearings connecting the inner ends of the axle members with the seat-frame, a propelling

mechanism, and separate steering devices connected with said slidable bearings to adjust the axle members individually and to dis- 70 alined positions.

7. A bicycle comprising a suspended seat-frame, a divided axle having its members disposed above the horizontal plane of said seat-frame, bearings fitted to the end portions of the axle and connected with the seat-frame, horizontally-slidable bearings mounted on the seat-frame and connected with the inner bearings of the axle members, means for individually shifting said slidable bearings and 80 changing the relation of the axle members, a propelling mechanism, and suitable carrying-wheels mounted individually on the axle members.

8. In a bicycle, the combination of a suspended seat-frame, a divided axle having its members connected with the said frame by pivotal and horizontally-slidable bearings, and means for holding the slidable bearings normally in line with the pivotal bearings, and 90 steering devices connected separately with said slidable bearings.

9. In a bicycle, the combination of a divided wheeled axle having independently-shiftable members, a seat-frame suspended 95 yieldably and pivotally from the end portions of said axle members, a propelling mechanism, and separate steering devices connected individually with the axle members.

10. In a bicycle, the combination of a divided wheeled axle having its members separated to provide an intermediate space, a frame disposed below said axle and yieldably suspended therefrom, a seat disposed in the space between the adjacent ends of the axle 105 members and yieldably supported on the said frame, and means for propelling and steering the bicycle.

11. A bicycle comprising a divided wheeled axle, a seat-frame suspended from said axle 110 and provided with horizontal guide-bars, bearings supporting the axle members and slidably fitted to said guide-bars, springs to normally draw said bearings and the axle members in alinement with each other, and levers 115 fulcrumed on the seat-frame and connected individually to the slidable bearings.

12. A bicycle comprising a seat-frame, a divided wheeled axle having its members shiftably connected with said seat-frame for adjustment thereon in horizontal planes, bearings fitted to the outer portions of the members of said axle, stems carried by the bearings and fitted loosely in the seat-frame to permit the stems to have a turning and slid- 125 able movement with the bearings and axle members relative to said frame, and cushion-springs seated against the frame members and the stems on said bearings to absorb the shock on the frame.

13. A bicycle comprising a divided wheeled axle having its members separated to provide an intermediate space, a frame yieldably suspended from said axle, a vertically-movable

seat guided on the said frame and disposed in the space between the adjacent ends of said axle members, means to cushion the slide-
5 able movement of the seat on the frame, a horizontally-slidable bearing for each member of the axle, means for operating said bearings, and independent sets of propelling de-
vices connected with the members of said axle.

14. A bicycle comprising a divided wheeled
10 axle, a seat-frame suspended from the mem-
bers of said axle, propelling-treadles inde-
pendently supported on the seat-frame, a pull-rod attached to one end of each treadle,
ratchets carried by the inner ends of the mem-
15 bers of said axle, driving-levers fulcrumed on
the seat-frame, links connecting the other
ends of said treadles with the driving-levers,
and pawls carried by the said levers and en-
gaging with the ratchets.

20 15. A bicycle comprising a seat-frame hav-
ing continuous upper and lower bars suitably
united by intermediate frame members, a di-
vided axle provided with carrying-wheels,
pivotal bearings connected with the end por-
25 tions of the frame and the axle members,
horizontally-slidable bearings mounted on
said frame and receiving the inner ends of
the axle members, a seat supported by the
frame between the axle members and the slide-
30 able bearings therefor, independent propel-
ling devices mounted on the frame and con-
nected separately with the axle members, and
separate steering devices disposed at the sides
35 of the seat and connected with the slide-
able bearings of said axle members.

16. In a bicycle, the combination of a di-
vided axle, a wheel on each member of the
axle, a frame suspended from the outer ends
40 of the members of the axle, horizontally-slid-
able and spring-pressed bearings carried by
the frame, and in which the inner ends of the
axle members are mounted, and means for
sliding said bearings.

45 17. In a bicycle, the combination of a di-
vided axle, a wheel on each member of the
axle, a frame suspended from the outer ends
of the members of the axle, horizontally-slid-
able bearings carried by the frame and in
50 which the inner ends of the members of the
axle are mounted, means for holding the bear-

ings in position to retain the axles alined, and
means for sliding the said bearings to steer
the bicycle.

18. In a bicycle, the combination of a di-
vided axle, wheels on the members of the 55
axle, a frame yieldingly suspended from the
members of the axle adjacent to the wheels,
horizontally-slidable bearings carried by the
frame and in which the inner ends of the
members of the axle are mounted, springs 60
connected with the sliding bearings and hold-
ing the members of the axle normally alined,
and means connected with said bearings for
sliding them against the action of the springs.

19. In a bicycle, the combination of a di-
vided axle, wheels on the members of the 65
axle, a frame suspended from the outer ends
of the axle members, horizontally-slidable
bearings carried by the frame and in which
the inner ends of the axle members are mount-
ed, levers connected with said bearings for
70 sliding the same, a frame carried by the main
frame, a seat mounted in the said frame in
the space between the axle members and in a
plane below the same, pedals pivoted on the 75
seat-frame, and a driving mechanism with
which the pedals are connected.

20. In a bicycle, the combination with a di-
vided axle, wheels on the axle members, a 80
frame yieldingly suspended from the outer
ends of the axle members, sliding and spring-
pressed bearings carried by the frame and in
which the inner ends of the axle members
are mounted, hand-levers connected with said
85 bearings for sliding them, a seat-frame car-
ried by the main frame, a yieldingly-support-
ed seat mounted in the seat-frame, pedals
pivoted between their ends on the seat-frame,
a pull-rod connected with one end of each
90 pedal, a link connected with the other end of
the pedal, and pawl-and-ratchet mechanisms
for operating the bicycle and with which the
said links are connected.

In testimony whereof I have signed my
name to this specification in the presence of 95
two subscribing witnesses.

BENJAMIN F. MODISETT.
